CLAIM

The ornamental design for a sensor housing, as shown and described.

DESCRIPTION

FIG. 1 is a top, front, right-side perspective view of a sensor housing;

FIG. 2 is a right-side view thereof;

FIG. 3 is a left-side view thereof;

FIG. 4 is a front view thereof;

FIG. 5 is a back view thereof;

FIG. 6 is a top view thereof;

FIG. 7 is a bottom view thereof; and,

FIG. 8 is a top, front, right-side perspective view thereof shown with a vehicle for environmental context.

The dashed broken lines depict portions of the sensor housing that form no part of the claimed design. The dashed broken lines showing a vehicle in FIG. 8 depict environment and forms no part of the claimed design. The dot-dashed broken lines represent boundaries of the claimed sensor housing and form no part of the claimed design.

1 Claim, 8 Drawing Sheets
